Max Groetsch and Bernardine M. Sprague,
Pittsburgh, Pa.

Application October 12, 1944, Serial No. 115,740

Term of patent 14 years

(Cl. D44—22)

To all whom it may concern:

Be it known that we, Max Groetsch, a citizen of the United States and a resident of Pittsburgh, in the county of Allegheny and State of Pennsylvania, and Bernardine M. Sprague, a citizen of the United States and a resident of Pittsburgh, in the county of Allegheny and State of Pennsylvania, have invented a new, original, and ornamental Design for a Combined Salt and Pepper Shaker, of which the following is a specification, reference being had to the accompanying drawing, forming part thereof.

Figure 1 is a side elevational view of a combined salt and pepper shaker, showing my new design.

Figure 2 is a front elevational view as viewed at right angles to Figure 1.

Figure 3 is a top plan view, and

Figure 4 is a bottom plan view thereof.

We claim:

The ornamental design for a combined salt and pepper shaker, as shown.

MAX GROETSCH.
BERNARDINE M. SPRAGUE.
